GARMENT CONSTRUCTION

Aaron A. Goldstein, Philadelphia, Pa., assignor
to Coat Craft Company, Philadelphia, Pa., a
corporation of Pennsylvania

Application December 26, 1946, Serial No. 718,533

1 Claim. (Cl. 2—85)

1 The present invention relates generally to overcoats and more particularly to an improvement in the bottom hem construction thereof, it being among the principal objects of the present invention to facilitate ready and convenient lengthening of a coat when occasion requires.

More specifically, it is an object of the present invention to provide an overcoat or other such garment having a conventionally constructed bottom hem with a member normally concealed within the fold of the hem and adapted to be let out in such manner that it becomes an extension of the hem dropped below its normal, unaltered position with consequent increase in the length of the coat.

Further important objects of the present invention are to provide an extensible hem at the bottom of a coat which is neat and simple in its construction and appearance; which is so arranged as to eliminate any noticeable bulge in the hem when either unextended or extended; which is of normal appearance in its original construction, that is, prior to extension thereof; and which, even when extended to lengthen the coat, is of neat and inconspicuous appearance.

With the foregoing and objects which will be apparent hereinafter, it will be understood that the present invention consists substantially in the combination, construction, location and relative arrangement of parts, all as will be described in detail hereinafter, as shown in the accompanying drawings and as finally pointed out in the appended claim.

In the accompanying drawings, which illustrate a preferred construction and embodiment of the present invention:

Figure 1 is a fragmentary view of an overcoat embodying the present invention having a portion of the lining broken away in order to display some of the details of construction;

Figure 2 is a sectional view taken on line 2—2 of Figure 1;

Figure 3 is an enlarged detailed sectional view;

Figure 4 is a sectional view similar to Figure 2 showing the garment in its extended or lengthened condition; and

Figure 5 is a sectional view taken on line 5—5 of Figure 1.

Referring now to the drawings, it will be observed that the main body portion 10 of the overcoat is provided at its lower edge with an upwardly turned hem 11, this hem being continuous with the main body portion 10 to provide therewith a folded bottom edge 12, which may be suitably creased as by pressing. The vertical edges

of the main body portion of the garment are provided, as is customary, with inturned flaps 13 to provide a finished appearance to the overlapping edges of the garment, which edges may be provided, if desired, with buttons and buttonholes in accordance with conventional practice. The lining 14 of the garment is preferably of the type which hangs freely at its bottom edge, the vertical edges of the lining being each secured to the vertical edge of the coat, as at 15, such construction being common in garments of this type.

In accordance with the present invention, a coupling member is interposed between the free edge of the upturned bottom hem 11 and the outer main body portion 10 of the coat, this member being normally concealed within the fold of the hem and having as its function to connect said free edge of the hem to said main body portion when the hem is lowered to lengthen the coat. More specifically, this coupling member consists of a strip 16 of relatively thin but strong material, this strip 16 being coextensive in length with that of the hem 11. Preferably, the upper edge of this coupling strip 16 is folded over and secured to the free edge of the hem 11, as at 17, to provide a neat appearing, finished edging 18 for said hem, its lower edge being folded upon itself and secured, as at 19, to the outer main body portion of the coat, as by a line of stitching of a character not noticeable upon the outer surface of the coat, such line of stitching being designated in Figure 1 by the reference numeral 20. In addition, the finished edge 18 of the hem is secured, as at 21, to the main outer body portion 10 of the coat by a line of stitching 22 similar in character to the line of stitching 20. Preferably, the lines of stitching 20 and 21 are of the kind known as tacking, it being a simple matter to rip out such stitching as desired without injury to the fabric. If desired, the upper line of tacking 21 may be dispensed with entirely, it having been found that even in the absence of such tacking the hem 11 in its original condition shown in Figure 2 may be retained in position by pressing the same.

In its normal condition, as originally made up or manufactured, the coupling strip 16 is disposed within the fold of the upturned hem 11, as shown in Figures 2 and 3, in which position the strip lies substantially flat between the overlapping portions of the hem with its opposite edges secured respectively, as at 19 and 21, to vertically spaced parts of the outer portion 10 of the coat. As thus constructed, the strip 16 is concealed from view and the hem 11 is thus of normal appearance. When it is desired to

lengthen the coat, it is merely necessary to rip out the upper line 24 of light stitching or tacking, whereupon the hem 11 will drop into its lowered position, as shown in Figure 4, the upper edge 18 of the hem being, however, coupled to the outer body portion 10 of the coat by the coupling strip 16, which becomes an extension, as shown in Figure 4, of the hem 11. Of course, when so extended the strip 16 is exposed to view, but this is in no sense objectionable because normally it is still covered by the lining 14 of the coat. By forming the coupling strip 16 of a material which matches the lining, its appearance would not be objectionable even should it not be completely covered by the lining.

It will be understood, of course, that the present invention is not limited in its application to the hems of coats, but may also be employed with equally good effect to lengthen coat sleeves and the like, the lengthening being obtained in all applicable cases without any sacrifice in neatness and attractive appearance of the garment, both in its original and altered state. Inasmuch as the coupling strip is disposed in flat condition within the hem, it introduces no excessive bulk in the zone of its application and when the gar-

ment hem is pressed no evidence of the presence of the coupling strip is discernible from external view of the hem.

What is claimed as new and useful is:

5 A garment construction of the character described, a main body portion having an inwardly turned hem, and a band of flexible material interposed between the hem and the main body portion, said band having one longitudinal edge 10 thereof attached to the upper edge of the hem and its opposite longitudinal edge attached to the main body portion along a line intermediate the width of the hem, the upper edge of the hem being attached to the main body of the garment by readily removable stitching.

15 AARON A. GOLDSTEIN.
